UNITED STATES PATENT OFFICE.

FRANK E. SIMPKINS, OF YOUNGSTOWN, OHIO.

TUBE-ROLLING MILL.

1,141,427.

Specification of Letters Patent.

Patented June 1, 1915.

Application filed August 19, 1912, Serial No. 715,906. Renewed December 4, 1914. Serial No. 875,533.

To all whom it may concern:

Be it known that I, FRANK E. SIMPKINS, a resident of Youngstown, in the county of Mahoning and State of Ohio, have invented 5 certain new and useful Improvements in Tube-Rolling Mills, of which the following is a specification.

This invention relates to rolling mills, and has particular reference to a mill for cross- 10 rolling such as is generally used for rolling seamless tubes, and the primary object is to provide simple and efficient roll mountings, together with improved means for adjusting the rolls relatively to each other and to the 15 roll pass, the several adjustments being under accurate control and of such scope as to meet the varying requirements peculiar to cross-rolling.

A further object is to provide a frame of 20 improved construction in which the roll mountings are arranged.

In the accompanying drawings, Figure 1 is a view of the improved mill, one-half thereof being shown in top plan and the 25 other half illustrating one of the roll mountings in sectional plan on line 1—1 of Fig. 2, and with the upper portions of the frame sides removed to illustrate the slideable roll-supporting carriage. Fig. 2 is an elevation 30 of the mill, one-half thereof being a front elevation, and the other half a vertical section on line 2—2 of Fig. 1. Figs. 3 and 4 are sectional elevations on lines 3—3 and 4—4, respectively, of Fig. 1. Fig. 5 is a 35 section of the frame and carriage in the plane of line 2—2 of Fig. 1 with the roll mounting removed from the carriage. Fig. 6 is a sectional detail of the gearing for adjusting the roll about a horizontal axis.

40 The portions of the mill at opposite sides of the roll pass are duplicates one of the other save for the reversely positioned rolls which result in cross-rolling, and it will therefore be understood that the following 45 description of the roll mountings and adjustments phrased in the singular is applicable to the mechanism at either side of the pass.

The mill is preferably located on a heavy 50 foundation plate 2 formed with marginal upright lugs 3 between which the lower longitudinal members 4 of the main frame are secured by wedges 5. The longitudinal sides of each half of the frame consist each 55 of the bottom beam 4 above referred to and a top beam 6, the beams being secured to

gether by bolts 7. There are preferably two frame parts—one for each side of the mill with a bolt 8 connecting the parts at the front, and a similar bolt 9 at the rear.

60 The under faces of opposite beams 6 are recessed on their inner sides to form longitudinal slideways 10 for the plate-like carriage 11 which carries the roll mounting. The carriage is adjusted toward and from 65 the roll pass by the hand-operated screw shaft 12, and after being adjusted it is secured in slideways 10 against vertical displacement by the elongated longitudinally movable wedges 13 each formed with a bolt-like extension 14 which projects through the end of the frame where it is provided with an adjusting nut 15.

70 The inner edge 16 of carriage 11 is of semi-circular form to embrace base 17 of circular casing 18, the latter being semi-circular in the plane of the carriage as shown in Fig. 1, and the casing is supported on the carriage by the semi-circular flange 19, the flange being formed with concentrically 75 grooved slots 20 to receive clamping bolts 21 projected upwardly from the carriage.

80 The face of each casing 18 adjacent the roll pass is formed with a bearing recess 22 which is circular around a horizontal axis 85 and the recess is stepped into reduced diameters from front to rear, as shown. Fitting this recess is the circular and complementarily stepped head 23 which is recessed on its front face at 24 to receive the roll 25, 90 the spindle 26 of the latter being journaled on the front face of the head, as shown.

A bolt passage extends rearwardly 95 through the center of head 23 and through casing 18, and arranged therein is clamping bolt 27 provided with a nut at its outer end on the exterior of the casing 18 for securing or clamping head 23 after it has been adjusted as desired.

100 Head 23 is adjustable about a horizontal axis—defined by bolt 27—for varying the vertical inclination of the roll, and with the clamping bolt slackened this adjustment is accomplished by the worm gear 28 mounted preferably in the top of casing 18 and meshing with gear teeth 29 on head 23, Fig. 6, the spindle of worm 28 having a squared extremity to receive a wrench. The worm gear is in itself a lock for the head, and it, together with the clamping bolt 27, securely 110 hold the head with the roll in the angular position to which it is adjusted.

For adjusting the mounting about a vertical axis as required for adjusting the roll face laterally with relation to the pass, wrench-turned screw-bolts 30 have swivel connections with casing 18, as indicated at 5 31, and extend outwardly through nuts 32 fixed to carriage 11 so that upon turning the rods casing 18 may be adjusted on carriage 11 about a vertical axis and then secured by 10 blots 21.

11 The several adjustments are effected with mechanical precision and are positively maintained and provide for every roll adjustment necessary for cross-rolling.

15 I claim:—

1. In a mill for cross rolling, the combination of opposed rolls normally in fixed position relatively to the pass formed thereby, and a normally fixed support for each roll 20 adjustable about axes disposed at right angles to each other.

2. In a mill for cross rolling, the combination of opposed rolls normally in fixed position relatively to the pass formed thereby, 25 and a normally fixed support for each roll adjustable about a vertical axis which intersects the roll.

3. In a mill for cross rolling, the combination of opposed rolls normally in fixed position relatively to the pass formed thereby, 30 and a normally fixed support for each roll adjustable about a vertical axis and also about a horizontal axis.

4. In a mill for cross rolling, the combination of opposed rolls normally in fixed position to form a horizontal roll pass, and a 35 normally fixed support for each roll adjustable about a perpendicular axis which intersects the roll.

40 5. In a mill for cross rolling, the combination of opposed rolls normally in fixed position to form a horizontal roll pass, and a normally fixed support for each roll with each roll adjustable about axes disposed at right angles to each other and with one of 45 said axes disposed at right angles to the axis of the roll pass.

6. In a mill for cross rolling, the combination of opposed rolls normally in fixed position 50 relatively to the pass formed thereby, a normally fixed support adjustable about axes disposed at right angles to each other, and means for adjusting each roll support bodily toward and away from the other 55 support.

7. In a mill for cross rolling, the combination of normally fixed supports at opposite sides of a roll pass with each support formed with a curved seat which faces the pass, normally 60 fixed roll mountings adjustable in said seats about horizontal axes, and opposed rolls journaled in the roll mountings.

8. In a mill for cross-rolling, the combination of a roll, a head in which the roll is 65 mounted, a casing in which the head is rota-

table for adjusting the roll, and clamping means located at the axis of rotation of the head for fixing the latter to the casing.

9. In a mill for cross-rolling, the combination of a roll, a head in which the roll is 70 mounted, a casing in which the head is rotatable for adjusting the roll, and a clamping bolt extending through the head and casing and about which the head is rotatable for adjusting the roll. 75

10. In a mill for cross-rolling, the combination of a roll, a circular head in which the roll is mounted, a casing having a circular bearing in which the head rotates, a bolt for securing the head to the casing and about 80 which the head is rotatable, and intermeshing gears on the casing and head for adjusting the latter within the casing.

11. In a mill for cross-rolling, the combination of a roll, a circular head having a recessed face in which the roll is mounted, a casing in which the head is adapted to rotate, the head formed with a bolt passage through its axial line and through the casing, a clamping bolt extending through said 90 passage, and head rotating means. 95

12. In a rolling mill, the combination of a roll, a roll mounting, and a normally fixed horizontal support provided with a curved seat in which the mounting is adjustable 95 about a vertical axis.

13. In a rolling mill, the combination of a roll, a roll mounting, a fixed frame, a mounting-supporting slide movable horizontally in the frame, means for axially 100 adjusting the roll mounting on the slide about a vertical axis, and slide adjusting means.

14. In a rolling mill, the combination of a fixed frame, a carrier slidable horizontally in the frame toward and from the roll pass, a roll mounted on the carrier, and means for wedging the carrier vertically within the frame for holding it against 105 horizontal displacement. 110

15. In a rolling mill, the combination of a frame formed with slideways, a carrier movable in the slideways toward and from the roll pass, wedges within and adjustable longitudinally of the slideways for adjusting the carrier vertically therein, a roll, and roll mounting positioned on the carrier. 115

16. In a rolling mill, the combination of a base plate formed with upwardly extending flanges, a frame located between the flanges, wedges inserted between the flanges and frame for holding the latter against displacement, rolls, and roll mountings arranged within the frame. 120

17. In a mill for cross rolling, the combination of opposed rolls normally in fixed position relatively to the pass formed thereby, and a normally fixed support for each roll adjustable about two different axes with 125 said axes intersecting each other and with 130

both axes intersecting the roll which is sustained by said support.

18. In a mill for cross rolling, the combination of opposed rolls normally in fixed position relatively to the pass formed thereby, and a normally fixed support for each roll adjustable about a horizontal axis which intersects the roll axis and also adjustable about a vertical axis which intersects the roll.

19. In a mill for cross rolling, the combination of a fixed frame, opposed carriages slideable in the frame toward and from each

other, carriage sliding means, a roll support adjustable on each carriage about a horizontal axis and also about a vertical axis, and opposed rolls—one journaled in each support and with each roll intersected by the axes about which its support is adjustable.

In testimony whereof I affix my signature in presence of two witnesses.

FRANK E. SIMPKINS.
